R. J. GILMORE.
HOOP IRON STRETCHER.
FILED JULY 2, 1918.

Inventor:
Robert Jackson Gilmore.
per *A. W. Blucker,*
Attorney.

UNITED STATES PATENT OFFICE.

ROBERT JACKSON GILMORE, OF ASSAM, BRITISH INDIA.

HOOP-IRON STRETCHER.

Application filed July 2, 1918. Serial No. 243,081.

To all whom it may concern:

Be it known that I, ROBERT JACKSON GILMORE, a subject of His Majesty King George V, whose address is Dooria Tea Company 5 Limited, Badlipar post office, Assam, British India, have invented Improved Hoop-Iron Stretchers, of which the following is a specification.

The object of this invention is the provision of an improved apparatus for efficiently stretching hooping iron over or around boxes and packages.

My invention will be described with reference to the accompanying drawings in which like letters of reference indicate like parts, and in which:—

Figure 1 is a side elevation; and

Figure 2 a partial cross section of the same on line X X.

20 My instrument consists of a handle or lever A provided with a projection or lug B at its end. To this lug the gripping lever C is pivoted at D. This pivot may be a stud bolt or rivet.

25 The pivot hole in the head E of the gripping lever is drilled eccentrically so that on moving the lever C towards the handle or lever A a cam action comes into play. Gripping surfaces F F' are formed on the 30 heads of the handle and the gripping levers respectively.

These gripping surfaces may if preferred be serrated, roughened or toothed, or may be smooth hardened surfaces. I have however 35 found that a smooth surface on the main lever A with a roughened surface on the gripping face of the head E on the small lever C to be the most satisfactory combination.

40 The gripping surfaces are so formed that hoop iron may be passed between the two surfaces, and then simply by forcing the gripping lever C towards the handle A the hoop iron is firmly held and prevented from 45 slipping. Any tendency of the hooping iron to slip through the gripping surfaces causes them to grip more securely together.

In using my appliance, the end of the hooping iron having first been attached to 50 the box or case to be hooped, it is passed

between the gripping surfaces F and F'. The instrument is then placed against the edge of the box or case and the gripping lever C closed to grip the hoop iron. The instrument is then forced down levering 55 against the box, and the cammed formation of the gripping surfaces causes them to hold more and more securely as the lower end of A is forced down, whereby stretching the hooping iron to the requisite tension and at 60 the same time automatically pressing the planks of the box or case firmly into their correct position and thereby leaving the operator both hands free for nailing or fixing the hooping iron to its final position. 65

The object of the small lever C is to ensure an easy disengagement of the apparatus from the hooping irons, as by pulling the lever C away from the lever A the grip at F F' is instantly released. 70

Having now particularly described and ascertained the nature of my said invention and in what manner the same is to be performed, I declare that what I claim is:—

An instrument for use in stretching hooping iron for containers, comprising a lever handle, an enlarged part formed on one end of the lever handle and projecting to one side of the center line of the handle to form a fulcrum for the instrument, a hand 80 lever having a cam part eccentrically pivoted on the said enlarged part, the said cam being provided with peripheral serrations for gripping the hooping iron when the lever handle and hand lever are substantially parallel to each other, and the said enlarged part being recessed to form an inclined bearing surface adjacent to the periphery of the said cam and to receive the lever handle in such manner that the 85 center line of the hooping iron gripped by the instrument is intersected by the center line of the lever handle. 90

In testimony whereof I hereto affix my signature in presence of two witnesses, this 95 sixteenth day of April 1918.

ROBERT JACKSON GILMORE.
